UNITED STATES PATENT OFFICE.

OTTO SELG AND CARL GUNTRUM, OF NEW YORK, N. Y.

LIQUID-FILTER.

SPECIFICATION forming part of Letters Patent No. 739,562, dated September 22, 1903.

Application filed April 20, 1903. Serial No. 153,369. (No model.)

To all whom it may concern:

Be it known that we, OTTO SELG and CARL GUNTRUM, citizens of the United States, residing at New York city, (Brooklyn,) county of 5 Kings, and State of New York, have invented certain new and useful Improvements in Liquid-Filters, of which the following is a specification.

This invention relates to a filter for beer, ale, water, and other liquids, which is so constructed that it can be readily taken apart and cleaned and that a filtrate of superior clearness is obtained.

In the accompanying drawings, Figure 1 is a plan of our improved filter; Fig. 2, a vertical central section of the same on line 2 2, Fig. 1; Fig. 3, a horizontal section on line 3 3, Fig. 2, with the filtering body removed; Fig. 4, a section through the compressing-ring 20 with hand-bars attached; Fig. 5, a detail of the compressing-ring, showing it lowered; and Fig. 6, a similar detail showing it raised.

The letter *a* represents the cylindrical shell of the filter, having a base *b* and inclosing two 25 concentric foraminated cylinders *c d*, fitted within annular grooves *b' b* of base *b*. Each cylinder is coarse-meshed and is provided with a fine-meshed lining *c' d'*. By the construction described there are formed three 30 chambers *e f g*, the outer chamber *e* being formed between the shell *a* and cylinder *c*, the central chamber *f* being formed between the cylinders *c d*, and the inner chamber *g* being formed within the cylinder *d*. At its upper 35 end the shell *a* is flanged, as at *a'*, to support an annular plate or outer cover *h*, which closes the outer chamber *e* and is flanged, as at *h'*, to grasp the upper edge of outer cylinder *c*, to which it may be soldered. A gasket *i*, interposed between the flange *a'* and plate *h*, forms 40 a water-tight joint. The inner chamber *g* is closed by a second cover *j*, having a flange *j'*, which grasps the upper edge of the inner cylinder *d*, to which it may be soldered. Upon 45 the cover *h* is mounted an open cruciform third cover *k*, having a strengthening-web *k'* and removably secured to the shell *a* by hinged locking-bolts *k*, that pass likewise through peripheral slots of the cover *h*. A 50 central clamping-screw *l*, passing through a tapped opening of cover *k*, bears upon the cover *j*. By the arrangement described the

parts are properly assembled and connected, while the outer and inner chambers are tightly closed.

The water or other liquid to be filtered enters the outer chamber *e* through an inlet-pipe or pipes *m* and passes through the central chamber *f* into the inner chamber *g* and through an auxiliary filtering-chamber *v*, hereinafter described, out through outlet-pipe *n*. The central chamber *f* is the filtering-chamber proper and contains the pulp or other filtering-body *r*. This pulp is tightly packed and compressed by means of a ring *o* of a 65 width to readily enter the chamber *f*. The bottom of ring *o* is concaved, Fig. 6, and to this bottom is screwed at *p'* a downwardly-curved flexible gasket *p*. Clamping-screws *q*, engaging tapped openings of upper cover *k*, bear 70 upon the top of ring *o* and serve to force the same downward upon the filtering-body *r*, Figs. 5 and 6.

In filling the chamber *f* with the filtering-body the latter is introduced in small quantities and tamped from time to time by the ring *o*. For tamping purposes handles *s* are screwed into holes *o'* of ring *o* while the gasket *p* is removed. After the chamber *f* is properly filled the bars *s* are unscrewed from the ring 85 and the gasket is reattached to the same. The ring is then placed upon the surface of the filtering-body, so that the gasket *p* projects downward, Fig. 6. By now tightening up the screws *q* the ring is forced against the filtering-body and the gasket is laterally expanded along the concave bottom of the ring to form a tight joint, Fig. 5.

Within the inner chamber *g* is fitted a low foraminated cup *t*, covered on its top, sides, 90 and bottom by filtering-cloth *u* and forming a small auxiliary filtering-chamber *v*, which communicates with the outlet-pipe *n*.

In use the filtering material is tamped into the chamber *f* and the cover *k* is fitted in place. The bolts *k* are swung up and tightened to lock the cover *k* to the shell *a*, thus closing chamber *e*. The screws *q* and *l* are then tightened to force the ring *o* and cover *j* down and to thus properly close the filtering-chamber *f* and the inner chamber *g*.

The water or other liquid entering chamber *e* will be thoroughly filtered within chamber *f* and by the auxiliary filtering-chamber *v* and

will then pass out through the outlet *n*. The filter may be readily taken apart and cleaned by swinging down the bolts *k*², removing the upper cover, and withdrawing the cylinders.

5. What we claim is—

1. A filter composed of a shell, a pair of concentric foraminated cylinders to form three concentric chambers, filtering material within the central chamber, a cover closing the outer chamber, a second cover closing the inner chamber, a ring within the central chamber, and means for lowering said ring upon the filtering material, substantially as specified.

15 2. A filter composed of a shell, a pair of concentric foraminated cylinders to form three concentric chambers, filtering material within the central chamber, a cover closing the outer chamber, a second cover closing the inner chamber, a ring within the central chamber, a third cover, and set-screws on the third cover which engage the ring, substantially as specified.

3. A filter composed of a shell, a pair of concentric foraminated cylinders to form three concentric chambers, filtering material within the central chamber, a ring having a concave bottom, a flexible gasket secured to said bottom, a cover, and set-screws on the cover that engage the ring, substantially as specified.

4. A filter composed of a shell, a pair of concentric foraminated cylinders to form three concentric chambers, filtering material within the central chamber, a cover closing the outer chamber, a second cover closing the inner chamber, a ring within the central chamber, a flexible gasket secured to the ring, a third cover adapted to be locked to the shell, and set-screws on the third cover which engage the second cover and the ring, substantially as specified.

5. A filter composed of a shell, a pair of concentric foraminated cylinders to form three concentric chambers, filtering material within the central chamber, a cover closing the outer chamber, a second cover closing the inner chamber, a ring within the central chamber, a flexible gasket on the ring, a third cover adapted to be locked to the shell, set-screws on the third cover which engage the second cover and the ring, and an auxiliary filtering-cup within the inner chamber, substantially as specified.

Signed by us at New York city, (Manhattan,) 53 New York, this 18th day of April, 1903.

OTTO SELG.
CARL GUNTRUM.
